UNITED STATES PATENT OFFICE.

GEORGE A. WISE, OF PITTSBURGH, PENNSYLVANIA, ASSIGNOR TO SUTTON-ABRAM-
SEN ENGINEERING COMPANY, OF PITTSBURGH, PENNSYLVANIA, A CORPORATION
OF PENNSYLVANIA.

BAR-Straightening Machine.

Application filed August 12, 1922. Serial No. 581,497.

To all whom it may concern:

Be it known that I, GEORGE A. WISE, a citizen of the United States, residing at Pittsburgh, in the county of Allegheny and State of Pennsylvania, have invented a new and useful Improvement in a Bar-Straightening Machine, of which the following is a specification.

This invention relates to a gag press, or machine for the straightening of metallic bars by means of a pressing action.

The object of the invention is to provide a machine of this nature which embodies adjusting means for adapting the machine to bars of various form in cross section, and also means to adjust for bars of different length and for bars the distortion of which occurs in curvatures of different length and degree.

A further object of the invention is to provide a double acting gag press in which the above mentioned adjustments may be made independently on both ends of the machine, so that the press may act simultaneously to straighten two bars of different cross sectional form and degree of distortion.

In the accompanying drawings Figure 1 is a plan view of the machine; Fig. 2 is a side elevation thereof; Fig. 3 is an end elevation of the machine; and Fig. 4 is a fragmentary plan view illustrating one of the adjustments of which the machine is capable.

The machine comprises upright end members 1 and a table or platform 2 supported thereby. Beneath table or platform 2 are bearings 3 in which is mounted the main operating shaft 4 of the machine, extending transversely thereof. The operating shaft 4 may receive power either from some external source by means of a pulley 5 on the shaft; or may receive power from the electric motor 6, on the shaft of which is a pinion 7 meshing with a gear 8 on the operating shaft.

The operating or pressure heads 9 and 10 of the machine are secured to cross heads 11; which travel in guides 12, and which are pivoted at 13 to a walking beam or double acting pitman 14. This pitman 14 has an eccentric connection with a cross shaft 15 mounted in bearings 16. The cross

shaft 15 is operated by means of a gear 17 thereon which meshes with a pinion 18 on the operating shaft 4.

In straightening a bar, the bar rests against bufferheads 19 which are movably supported in transversely extending blocks 20. It is in the arrangement of block 20 and bufferheads 19 that the chief novelty of the present invention resides.

As will be seen particularly by reference to Figs. 2 and 3 of the drawings, the transverse blocks 20 are slidable in the table or platform 2 by means of longitudinal tongues 21 engaging in corresponding grooves 22 in the table or platform. Rigidly secured to each of the transverse blocks 20 are a pair of adjusting screws 23 which have a screw threaded engagement with end sills 24 on the table 2. On the outer extremities of these adjusting screws 23 are pinions 25 which mesh with gears 26 rotatably supported by pins 27 secured in the end frame members 1. The gears 26 may be rotated by means of handle members or manually operable levers 28.

It is thus possible to move the blocks 20 in either direction longitudinally of the table or platform 2.

The bufferheads 19 themselves are positioned by means of blocks 29; which have a dove tailed engagement with the transverse base blocks 20, and each of which is connected with one of the bufferheads 19 by means of a tenon 30. Through the blocks 29 of each set passes a screw 31 by means of which these small blocks may be adjusted along the base blocks 20. These adjusting screws 31 are turned by means of crank arms 32 secured to one extremity of each of the screws. In order that revolution of the adjusting screws 31 may move the bufferheads 19 of each pair in opposite directions, each of the adjusting screws is divided into two oppositely threaded portions each of which passes through one of the blocks 29. In Fig. 4 of the drawings the bufferheads 19 of one pair are shown in full lines in their most widely separated position, and in dotted lines in their mutually closest position.

It will be seen that the adjustment of the base blocks 20 longitudinally of the machine accommodates for bars of different width; so that a relatively narrow bar may be

straightened at one end of the machine and a relatively wide bar simultaneously straightened at the other end thereof.

It will further be seen that the adjustment 6 of each pair of bufferheads 19 in the blocks 20 permits the bars being acted upon to be properly supported against the action of the pressure heads 9 and 10 with relation to the length of the particular bars and the length 10 and degree of curvature of the deformations which are to be straightened out.

The machine of the present invention thus provides for two independent adjustments 15 at each end of a double acting straightening machine.

As the machine as illustrated and described is susceptible of a number of modifications without departing from the spirit of the invention which it embodies, the scope 20 of the invention is to be restricted only by the limitations contained in the appended 25 claims.

What I claim is:

1. In a machine for straightening metallic 25 bars the combination of pressure heads arranged to act upon bars at both ends of the machine, unitary means for actuating all the pressure heads of the machine, a backing block at each end of the machine and adjustable longitudinally thereof, and a pair 30 of buffer heads for supporting bars being acted upon mounted in each backing block and adjustable toward and away from each other therein independently of the longitudinal adjustment of the backing block 35 in which they are mounted.

2. In a machine for straightening metallic bars means for acting upon bars at both ends 40 of the machine to straighten the same, a pair of bar supporting members or buffer heads at each end of the machine, an adjusting

screw so arranged with relation to each pair of buffer heads that rotation of the screw in one direction acts to separate its associated buffer heads and rotation thereof in the opposite direction causes said buffer heads to approach each other, and mounting means adjustable longitudinally of the machine for each set of buffer heads. 45

3. In a machine for straightening metallic bars the combination of pressure heads arranged to act upon bars at both ends of the machine, unitary means for actuating all the pressure heads of the machine, a pair of bar supporting members or buffer heads at each 55 end of the machine, and an adjusting screw so arranged with relation to each pair of buffer heads that rotation of the screw in one direction acts to separate its associated buffer heads and rotation thereof in the opposite direction causes said buffer heads to approach each other. 60

4. In a machine for straightening metallic bars the combination of pressure heads arranged to act upon bars at both ends of the machine, unitary means for actuating all the pressure heads of the machine, an adjusting screw so arranged with relation to each pair of buffer heads that rotation of the screw in one direction acts to separate its associated buffer heads and rotation thereof in the opposite direction causes said buffer heads to approach each other, and mounting means adjustable longitudinally of the machine for each pair of buffer heads. 70

In testimony whereof, I hereunto set my hand.

GEORGE A. WISE.
